(57) **CLAIM**

The ornamental design for the pre-cut body tape for the knee, as shown and described.

DESCRIPTION

FIG. 1 is a perspective view of a pre-cut body tape for the knee;

FIG. 2 is a front view of a pre-cut body tape for the knee; and, FIG. 3 is a side view of a pre-cut body tape for the knee.

[The broken line showing of the human forms is for the purpose of illustrating how the pre-cut body tape for the knee is applied and forms no part of the claimed design.]
